US0D1058454S

(12) **United States Design Patent** (10) **Patent No.:** **US D1,058,454 S**
(45) **Date of Patent:** **** Jan. 21, 2025**

(54) **VEHICLE EXTENSION PEDAL**

(71) Applicant: **Shenzhen Linglu Technology Co., Ltd.**, Shenzhen (CN)

(72) Inventor: **Xinlong Chen**, Shenzhen (CN)

(73) Assignee: **Shenzhen Linglu Technology Co., Ltd.**, Shenzhen (CN)

(**) Term: **15 Years**

(21) Appl. No.: **29/959,068**

(22) Filed: **Aug. 23, 2024**

(30) **Foreign Application Priority Data**

Aug. 20, 2024 (CN) 202430529084.2

(51) **LOC (15) Cl.** **12-16**

(52) **U.S. Cl.**

USPC **D12/174**

(57) **CLAIM**

The ornamental design for a vehicle extension pedal, as shown and described.

DESCRIPTION

FIG. 1 is a top perspective view of a vehicle extension pedal, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the vehicle extension pedal, which form no part of the claimed design.

1 Claim, 8 Drawing Sheets
